UNITED STATES PATENT OFFICE.

GUY C. CROSS, OF DENVER, COLORADO.

PHOTOGRAPHIC-FILM-STRIP HANGER.

1,404,276.

Specification of Letters Patent. Patented Jan. 24, 1922.

Application filed January 8, 1920. Serial No. 350,201.

To all whom it may concern:

Be it known that I, GUY C. CROSS, a citizen of the United States, residing at Denver, in the county of Denver and State of Colorado, have invented new and useful Improvements in Photographic-Film-Strip Hangers, of which the following is a specification.

The present invention is directed to improvements in photographic film strip hangers, and means for quickly and easily attaching films to the same.

The object of the invention is to provide a device of this character constructed in such a manner that the operator can upon operating a foot treadle or other means, successively impale the upper ends of the film strips upon spurs forming a part of the rack, and actuate a clamping bar to positively hold the film strips engaged with the rack during the successive operations of developing, fixing, washing and drying the films.

With this and other objects in view, this invention resides in the novel features of construction, formation, combination and arrangement of parts to be hereinafter more fully described, claimed and illustrated in the accompanying drawings, in which:—

Figure 1 is a perspective view of the device showing the yoke in its position previous to placing the film strips on the rack.

Figure 2 is a similar view showing the clamping bar engaged with the film strips.

Figure 3 is an end view of the device showing the yoke and clamping bar in their normal or inoperative position.

Figure 4 is a fragmentary transverse sectional view showing the position of the yoke upon impaling the film strips on the spurs of the rack.

Figure 5 is a similar view showing the yoke in a position to force the clamping bar into engagement with the rack.

Figure 6 is a detail view of the film rack, showing the clamping bar in its operative position, and the same holding a number of film strips.

The device comprises a U-shaped frame 1, the side arms 2 of which terminate in ears 3, said ears being formed with perforations 4 for receiving securing devices for attaching the frame to a wall or other suitable support.

A yoke 5 is employed and has its arms 6 pivotally connected with the side arms 2

of the frame 1, as at 7, while suitably secured to the right 8 thereof is a bar 9, preferably formed from wood, the purpose of which will appear later. A bar 10 has its ends secured to the arms 6 of the yoke, and formed centrally of this bar is a perforation 11, in which is secured the lower end of a coil spring 12, the upper end of which is attached to a hook 13, said hook being secured in the wall or other support. This spring serves to normally hold the yoke 5 in its raised or inoperative position, as shown in Figure 1 of the drawings.

Suitably secured to the lower edge of the bar 9 is a strip of felt 14, the purpose of which will later appear.

Adjacent each end of the front bar 15 of the frame 1 are secured the lower ends of the post 16, and spaced therefrom, and also fixed to the bar 15 are stops 17, said stops and posts being secured to the outer face of said bar.

Suitably secured to the inner face of the bar 15, and adjacent the ends thereof are spring fingers 18, said fingers being bowed inwardly, and having their upper ends inclined, as at 19.

Removably associated with the frame 1 is a film rack 20, which is of conventional shape, but has its horizontal bar 21 provided with a plurality of spurs 22. A clamping bar 23 is provided, and is preferably formed from angle metal, the horizontal web of said bar being formed with a plurality of perforations 24, corresponding in number to the spurs 22. The ends of the bar 23 are formed with guides 25 which are adapted to slidably engage the vertical arms 26 of the rack 20, said arms terminating in handles 27.

A cord or wire 28 is employed, and has its upper end secured in the perforation 11, while the lower end thereof is connected to a treadle 29 of any suitable construction. Thus it will be seen that the yoke 5 can be swung downwardly upon pressing upon the treadle 29, and that both hands of the operator are free to manipulate the film strips 30. It will be of course understood that a number of film strips are engaged on the rack before the same is removed from the frame 1.

It will be noted that, when the rack 20 is engaged with the frame 1, the bar 21 thereof rests on the upper edge of the front bar 15. The bar 21 of the rack is prevented

from moving laterally in either direction with respect to the bar 15 by the stops 17 and fingers 18, said fingers also serving in conjunction with the posts 16 to prevent the 5 rack from tilting owing to the fact that the handles 27 are engaged between the fingers and posts. The fingers 18 also serve to hold the clamping bar 23 in its raised or inoperative position since the ends thereof are engaged with the inclined ends of the fingers, as more clearly shown in Fig. 3 of the drawings.

In using, the film strip is removed from the camera in a rolled state, as is usual, 15 after which it is unrolled sufficiently to permit the upper end to be placed on the spurs 22 of the rack 20. The yoke 5 is then swung downwardly through the medium of the treadle 29 and the wire or cord 28 until the strip 14 is penetrated by the spurs 22, and simultaneously said spurs penetrate the film strip 30. Upon releasing pressure on the 20 treadle 29 the spring 12 will act to swing the yoke 5 upwardly to its inoperative position, as shown in Figs. 1 and 3.

The film strip is then wholly unrolled and a weight 31 is attached to the lower end, after which another film is attached in the 30 same manner as the first, and the operation is repeated until the rack has its capacity of films.

When the rack is full of films downward pressure is brought to bear upon the clamping bar 23 forcing it past the spring fingers 35 18 and into the line of travel of the bar 9. The treadle is then depressed and the bar 9 with the felt strip 14 interposed forces the clamping bar 23 into engagement with the rack, whereupon the spurs 22 will enter the 40 perforations 24, thereby positively preventing accidental disengagement of the film strips from the rack.

No claim is made for the film rack per se, the rack being subject matter for a separate 45 application filed September 21, 1920, and bears Serial Number 411,699.

What is claimed is:

1. The combination with a film holding 50 rack, of a frame for removably supporting the rack, a yoke pivotally supported by the

frame, and means for moving the yoke into and out of engagement with the rack, as and for the purpose set forth.

2. The combination with a film holding 55 rack having a clamping bar slidably connected thereto, of a frame for removably supporting the rack and having a yoke pivotally connected therewith, and means for operating the yoke to move the bar into engagement with the rack, as and for the purpose set forth.

3. The combination with a film holding rack having spurs associated therewith, of a frame for removably supporting the rack, and having a yoke pivotally associated therewith, and means for operating the yoke to impale films successively upon the spurs.

4. The combination with a film holding 70 rack having a clamping bar slidably connected thereto, of a frame for removably supporting the rack and having a yoke pivotally supported thereby, and means for operating the yoke to successively engage the rack and the bar, as and for the purpose set forth.

5. The combination with a film holding 75 rack, of a frame for removably supporting the rack and having a yoke pivotally connected thereto, means for yieldably holding the yoke out of engagement with the rack, 80 means for swinging the yoke into engagement with rack, the first named means also serving to move the yoke from engagement with the rack.

6. The combination with a film holding 85 rack having a clamping bar slidably connected thereto, of a frame for removably supporting the rack, a yoke pivotally associated with the frame, resilient fingers carried by the frame and adapted to engage 90 the bar to hold the same in an elevated position with respect to the rack, as and for the purpose set forth.

In testimony whereof I have hereunto set my hand in presence of two subscribing 95 witnesses.

GUY C. CROSS.
